CLAIM

We claim the ornamental design for a frame of a shaving unit, as shown and described.

DESCRIPTION

FIG. 1 is a top front perspective view of our new shaving unit frame;

FIG. 2 is a top view thereof;

FIG. 3 is a front view thereof;

FIG. 4 is a rear view thereof;

FIG. 5 is a bottom view thereof;

FIG. 6 is a right view thereof; and,

FIG. 7 is a left view thereof.

The broken line showing of the blade cartridge is for illustrative purposes only and forms no part of the claimed design.
